Primary Examiner — Richard E Chilcot

(**) Term: **14 Years**(57) **CLAIM**

The ornamental design for a computing device display screen with a computer-generated application launch interface, as shown and described.

(21) Appl. No.: **29/406,337****DESCRIPTION**(22) Filed: **Nov. 11, 2011**

FIG. 1 is a front view of a computing device display screen with a computer-generated application launch interface including a first category tab, under a first embodiment; FIG. 2 is a front view of a computing device display screen with a computer-generated application launch interface including a second category tab, under a second embodiment; FIG. 3 is a front view of a computing device display screen with a computer-generated application launch interface including a third category tab, under a third embodiment; and, FIG. 4 is a front view of a computing device display screen with a computer-generated application launch interface including a fourth category tab, under a fourth embodiment. The broken lines shown in the drawings are for the purpose of illustrating a display screen of a computing device, text, and other images, and form no part of the claimed design.
